UNITED STATES PATENT OFFICE

2,169,682

MECHANICAL TOY

Theodore R. Duncan, Los Angeles, Calif.

Application January 17, 1939, Serial No. 251,423

9 Claims. (Cl. 46—23)

This invention relates to toys and has special reference to that type of toy consisting of a set of differently formed pieces capable of being assembled in a variety of groups, each group imitating a physical object such as an animal or inanimate object.

One important object of the invention is to provide a set of such pieces capable of being connected by novel means without the use of pins 10 and sockets, bolts or other like means.

A second important object of the invention is to provide a novel set of toy forming pieces held in assembled relation by vacuum cups.

A third important object of the invention is 15 to provide a set of toy forming pieces certain of which are provided with indicia indicating the places of application of such vacuum cups.

A fourth object of the invention is to provide such indicia provided pieces with additional indicia indicating the nature of the pieces to be applied.

A fifth object of the invention is to provide an educational toy which can be manufactured at a fraction of the cost of most toys of this class and 25 which can therefore be marketed at a price that everyone can afford. This object is accomplished partly by the simplified form of the blocks themselves, and by the means provided to connect them to each other.

Another object of this invention is to provide 30 a toy that can be made of cheaper materials. As all pegs or metal parts are eliminated from this toy, softer woods can be used in their construction, the only requirements of manufacture being 35 that the blocks be given a smooth surface and then be covered with varnish or paint to provide a gripping surface for the suction cups.

A further object of this invention is to provide 40 a toy that can be made of lighter woods, as these are safer and more easily handled by children.

Still another object of this invention is to provide 45 a set of new and improved rubber suction cups especially adapted for assembling toy blocks. Certain of these suction cups are constructed so as to provide flexibility at the points of assembly to give the assembled toy animation, as the parts so assembled can be flexed or snapped. Other 50 suction cups are formed so as to give a maximum of rigidity between certain members, in order that the assembled toy will keep its shape when carried about in play.

A further object of this invention is to provide 55 single as well as double suction cups of increased gripping power. This being accomplished

by widening the neck of said cups; for in the case of suction cups as heretofore constructed the lips of the cup constrict almost completely when subjected to tension, said constriction resulting in a diminution of the suction area and a consequent lessening of gripping power. The ratio of the widths of the necks and the cups in my invention limits the amount of constriction possible, thereby increasing the gripping power of the cups.

With the above and other objects in view, the invention consists in general of certain novel details of construction and combinations of parts hereinafter fully described, illustrated in the accompanying drawings and particularly pointed out in the appended claims.

In the accompanying drawings, like characters of reference indicate like parts in the several views, and:—

Fig. 1 is a perspective view of the torso or body block.

Fig. 2 is a perspective view of the torso or body block in an upside down and reversed position to that shown in Fig. 1.

Fig. 3 is a perspective view of a trapezoidal block forming one of the pieces of the set.

Fig. 4 is a perspective view of an elongated bar forming a third piece of the set.

Fig. 5 is a perspective view of a cylindrical member forming a fourth piece of the set.

Fig. 6 is a perspective view of a rectangular block forming a fifth piece of the set.

Fig. 7 is a perspective view of a block of a form similar to Fig. 6 but having certain rounded edges.

Fig. 8 is an enlarged sectional view of the type of suction cup used with the piece shown in Fig. 5.

Fig. 9 is a section through the suction cup used with the pieces shown in Figs. 3, 6, and 7.

Fig. 10 is a view of a double suction cup for assemblies of parts not capable of being assembled by permanently attached cups.

Fig. 11 is a section through the suction cup used with piece shown in Fig. 4.

Fig. 12 is a perspective view of the cup shown in Fig. 9.

Fig. 13 is a perspective view of an assembly of the pieces to represent a "bucking broncho".

Fig. 14 is a perspective view of an assembly representing an army tank.

Fig. 15 is a perspective view of an assembly to represent a long range gun.

Fig. 16 is a perspective view of an assembly representing a clown.

Fig. 17 is a perspective view of an assembly representing a duck.

Fig. 18 is a perspective view of an assembly representing a totem pole.

It is to be understood that the set as sold may be made up of as many of each form of the pieces as desired.

The member or piece indicated in general at 20 is of substantially rectangular form with two of its end edges rounded as at 21. On each face this block is provided with one or more circles 10 22 forming indicia for positioning the suction cups, presently to be described, which connect the parts. Certain of these circles contain other indicia in the form of circles 23 indicating that the member shown in Fig. 7 is to be applied thereto. Other circles include squares 24 indicating the application of the form shown in Fig. 4. Still others contain crosses 25 indicating the place to apply the pieces like Fig. 5. However, it is not essential that the pieces be confined in application to the places thus marked but the indicia may be used to give instructions for the formation of various assemblies.

Fig. 3 has a body 26 of generally trapezoidal form provided on its sides with a representation 25 27 of a face. The longer rectangular face of this piece has a suction cup 28 secured in proximity to the square end of the piece. This piece is used for heads and other places in the assemblies, principally however for heads.

30 The piece shown in Fig. 4 consists of a flat strip 29 having a suction cup 30 provided with a flexible shank 31 fixed adjacent one end. Pieces of this character are used for ears, arms, wings, and the like, the flexible shank permitting vibration 35 of the pieces when attached so that a more life like effect is obtained.

The piece shown in Fig. 5 has a cylindrical body 32 provided on one end with a suction cup 33. This form is used for legs, necks and other 40 extended parts, the bodies 32 being capable of connection end to end as in Figs. 14 and 15.

The piece shown in Fig. 6 has a body 33' of 45 rectangular parallelepipedal form provided on one end with the representation 34 of a face. This piece has the cup 35 applied thereto.

The piece shown in Fig. 7 has a small oblong body 35 provided with a suction cup of the type indicated at 30.

The suction cup shown in Fig. 10 consists of 50 two cups 36 and 37 of like size and joined back to back by a shank 38. This double suction cup is used in joining two pieces, neither of which has suction cup at the point or points of junction. For instance, in making certain assemblies in sets 55 having two or more pieces 20, such pieces may be joined side by side or end to end by the interposition of one or more such suction cups. In like manner the pairs of pieces 35 may be connected in such assemblies as shown in Figs. 13, 60 14, and 17 and a pair of pieces 26 may be similarly connected as shown in Fig. 15.

It is obvious that the greater the number of the several pieces the greater will be the number of assemblages which can be made therewith. As here shown all the different assemblies can be made from a set containing one piece 20, two pieces each as at 26, 28 and 33', four pieces 35 and ten pieces 32.

70 There has thus been provided a simple, amus-

ing and instructive toy of the kind described and for the objects specified.

What is claimed, is:

1. A toy building set comprising a series of 5 differently shaped pieces, and suction cups for securing said pieces in assembled relation.

2. A toy building set comprising a series of 10 differently shaped pieces, and suction cups for securing said pieces in assembled relation, certain of said pieces having suction blocks permanently secured thereto.

3. A toy building set comprising a series of 15 differently shaped pieces, and suction cups for securing said pieces in assembled relation, certain of said pieces having suction cups permanently secured thereto and certain of the suction cups being double cups with the cups facing away from each other.

4. A toy building set comprising a series of 20 differently shaped pieces, and suction cups for securing said pieces in assembled relation, certain of said pieces having indicia thereon indicating 25 positions for the attachment of the suction cups of other pieces.

5. A toy building set comprising a series of 25 30 differently shaped pieces, and suction cups for securing said pieces in assembled relation, certain of said pieces having indicia thereon indicating positions for the attachment of the suction cups of other pieces and certain of the indicia being associated with other indicia for indicating the shape of the piece to be connected at the respective points.

6. A toy building set comprising a series of 35 differently shaped pieces, and suction cups for securing said pieces in assembled relation, certain of said pieces having suction cups permanently secured thereto, certain of said pieces having indicia thereon indicating positions for the attachment of the suction cups of other pieces. 40

7. A toy building set comprising a series of 45 differently shaped pieces, and suction cups for securing said pieces in assembled relation, certain of said pieces having suction cups permanently secured thereto, certain of the pieces having indicia thereon indicating positions for the attachment of the suction cups of other pieces. 50

8. A toy building set comprising a series of 55 differently shaped pieces, and suction cups for securing said pieces in assembled relation, certain of said pieces having suction cups permanently secured thereto and certain of the suction cups being double cups with the cups facing away from each other, certain of said pieces having indicia thereon indicating positions for the attachment of the suction cups of other pieces.

9. A toy building set comprising a series of 60 65 differently shaped pieces, and suction cups for securing said pieces in assembled relation, certain of said pieces having suction cups permanently secured thereto and certain of the suction cups being double cups with the cups facing away from each other, and certain of the indicia being associated with other indicia for indicating the shape of the piece to be connected at the respective points.
